UNITED STATES PATENT OFFICE

CLIFFORD M. WHITFIELD, OF SIOUX FALLS, SOUTH DAKOTA

DRESSING TABLE ATTACHMENT FOR BATHTUBS

Application filed February 16, 1931. Serial No. 516,246.

This invention relates to a bath and dressing table for infants, the general object of the invention being to provide means whereby the device can be adjustably attached to 5 different types of bath tubs, with means whereby the table top can be swung into inoperative position when not in use so that the bath tub can be used without removing the attachment therefrom.

10 This invention also consists in certain other features of construction and in the combination and arrangement of the several parts, to be hereinafter fully described, illustrated in the accompanying drawings and specifically pointed out in the appended claims.

In describing the invention, in detail, reference will be had to the accompanying drawings wherein like characters denote like or corresponding parts throughout the several 20 views, and in which:—

Figure 1 is a top plan view of a bath tub showing the legs of the device in section.

Fig. 2 is a top plan view showing the device attached to the bath tub.

25 Fig. 3 is a transverse sectional view through Fig. 2.

Fig. 4 is a front view.

Fig. 5 is a sectional detail view showing the table top in raised position.

30 Fig. 6 is a sectional view showing a modification used on a built-in tub.

Fig. 7 is a view of the rear leg of the attachment when used in built-in tubs.

Fig. 8 is a sectional view showing the means 35 for attaching a leg of the device to a bath tub.

In these drawings, the numeral 1 indicates the top of the table which is formed with a hinged section 2 the hinges of which are shown at 3. As shown in Fig. 2, the stationary part of the table top is of substantially 40 U-shaped form with the part 2 fitting in the opening formed by the U-shaped part when said part 2 is in lowered position.

When in lowered position, this part 2 rests 45 upon the projections 4 attached to the limbs of the U-shaped part, and these projections support the part 2 with its upper face flush with the upper face of the part 1. A tub or basin 5 is located in a hole in the part 2, with 50 its rim resting on the upper face of the part

2, and this tub is provided with a drain hole 6 closed by suitable closure.

The legs of the table are shown at A and each leg consists of a pair of sections 7 and 8 which overlap each other and are provided with a plurality of holes 9 for receiving the screws 10 so that the height of the table top from the floor can be adjusted by placing the bolts in certain of the holes 9 to lengthen or shorten the legs.

55 The lower end of each leg is formed with a hooked part 11 for engaging the rounded flange of the bath tub B and the beak of the hook-shaped part carries a set screw 12 for clamping the leg to the flange. A strip 13 of any suitable material can be placed between the flange and the hook-shaped part to prevent the legs from marring the tub.

A pair of slotted links 14 is pivoted to the 60 pair of brackets 15 attached to the under side of the hinge part 2, and the slot in each link is engaged by a projection 16 on a part of the device for limiting the upward movement of the part 2, as shown in Fig. 5.

A pair of slotted links 14 is pivoted to the 65 pair of brackets 15 attached to the under side of the hinge part 2, and the slot in each link is engaged by a projection 16 on a part of the device for limiting the upward movement of the part 2, as shown in Fig. 5.

When the device is to be used in a built-in bath tub such as shown at B', in Figs. 6 and 7, the lower section of each outer leg is formed with a curved part 17 and a detachable part 18 so that when the detachable part is bolted to the end of the lower section, said parts 18 and 17 will grip or engage the upper edge of the outer side of the bath tub as seen in Fig. 6.

70 Each inner leg is provided with a substantially L-shaped part 20 for engaging the upper edge of the built-in side of the tub as shown in Fig. 7. A strip 21 of any suitable material can be placed between the tub engaging part of the legs and the tub to prevent the legs from marring the tub as shown in Figs. 6 and 7.

75 From the foregoing, it will be seen that I have provided a combined bath and dressing table for infants, which can be easily and quickly attached to a bath tub of either the standard type or the built-in type, with means for adjusting the length of each leg of the table, as desired.

80 By providing the hinge part 2, this part can be swung upwardly into the position occupied in Fig. 5, when not in use, so that the 100

tub can be used without removing the device from the bath tub.

It is thought from the foregoing description that the advantages and novel features 5 of the invention will be readily apparent.

It is to be understood that changes may be made in the construction and in the combination and arrangement of the several parts provided that such changes fall within the 10 scope of the appended claims.

Having thus described my invention, what I claim as new is:—

1. A dressing table and bath for infants comprising a table top including a stationary 15 part and a hinged section, legs connected with the stationary part of the top, and means for attaching the legs to the rim of the bath tub whereby by moving the hinge part upwardly, the bath tub can be used without removing 20 the device from the bath tub.

2. An infant bath and dressing table comprising a top part consisting of a stationary substantially U-shaped part, a movable part normally fitted in the space formed by the 25 U-shaped part, hinges connecting the movable part with the bight part of the stationary part, a basin carried by the hinged part and legs connected with the stationary part and adapted to be connected with the rim of a 30 bath tub.

3. A dressing table and bath for infants comprising a top part including a substantially U-shaped stationary part, a movable part hinged at one edge to the bight of the 35 stationary part, means for normally holding the pivotal part in the space formed by the U-shaped part with its upper face flush with the upper face of the U-shaped part, said movable part having an opening therein, a 40 base fitting in the opening, legs connected with the stationary part, means at the lower ends of the legs for connecting them with the rim of a bath tub.

4. An infant's dressing table and bath comprising a top part, including a stationary part and a hinged part, a basin carried by the hinged part, legs depending from the stationary part, means for connecting the lower end of the legs to the rim of a bath tub, and 45 means for adjusting the length of each leg.

5. An infant's bath and dressing table comprising a top part and a stationary part of substantially U-shape, and a movable part fitting in the space formed by the U-shaped 55 part and having one edge hinged to the bight of said U-shaped part, said hinge part having an opening therein, a basin fitting in the opening, a slotted link pivotally connected with the under side of the hinge part, 60 a pin connected with a part of the table and passing through the slot for limiting the upward movement of the hinged part, legs depending from the stationary part, means at the lower ends of the legs for engaging a rim 65 of a bath tub.

6. An infant's bath and dressing table comprising a top part and a stationary part of substantially U-shape, and a movable part fitting in the space formed by the U-shaped part and having one edge hinged to the bight 70 of said U-shaped part, said hinge part having an opening therein, a basin fitting in the opening, a slotted link pivotally connected with the under side of the hinge part, a pin connected with a part of the table and passing through the slot for limiting the upward movement of the hinged part, legs depending from the stationary part, means at the lower ends of the legs for engaging a rim of a bath 75 tub, and means for adjusting the length of the legs.

In testimony whereof I affix my signature.
CLIFFORD M. WHITFIELD.
